UNITED STATES PATENT OFFICE.

LESTER STOWELL, OF WAUKESHA, WISCONSIN, ASSIGNOR OF ONE-HALF TO EMERY STOWELL, OF DUPLAINVILLE, WISCONSIN.

ADJUSTABLE SHINGLE-GAGE.

SPECIFICATION forming part of Letters Patent No. 769,508, dated September 6, 1904.

Application filed June 4, 1904. Serial No. 211,081. (No model.)

To all whom it may concern:

Be it known that I, LESTER STOWELL, a citizen of the United States, and a resident of Waukesha, in the county of Waukesha and State 5 of Wisconsin, have invented certain new and useful Improvements in Adjustable Shingle-Gages; and I do hereby declare that the following is a full, clear, and exact description thereof.

My invention has especial reference to gages attached to shingling-hatchets; and it consists in certain peculiarities of construction and combination of parts, as will be fully set forth hereinafter, in connection with the accompanying drawings, and subsequently claimed.

In the said drawings, Figure 1 is a view illustrating my device attached to a hatchet and in use. Fig. 2 is an edge view of the hatchet and attached device in the position shown in Fig. 1, the roof and shingles being shown in section on the line 2 2 of Fig. 1. Fig. 3 is a view in elevation of the hatchet and attached device, partly in section, on the line 3 3 of Fig. 2, but drawn to an enlarged 5 scale. Fig. 4 is a detail sectional view taken on the line 4 4 of Fig. 3. Fig. 5 is a perspective view of the gage proper; and Fig. 6, a like view of the gage-holder, which is designed to be attached to the upper end of the hatchet-handle.

Referring by numerals to the said drawings, 1 designates the handle; 2, the blade; 3, the handle socket or eye, and 4 the driving-head or hammer of an ordinary shingling-hatchet. 5 designates the gage-holder, which consists of an open-topped shell having a loop 6 at each end thereof, a threaded bore 7 through the center of the bottom wall, and countersunk openings 8 8, also through said bottom wall, one on each side of the said bore 7 for the passage of screws 9 9, whereby the said gage-holder is securely attached to the upper end of the hatchet-handle 1, the tops of the screw-heads being flush with the said bottom wall by reason of the described countersinking of the openings 8 8.

10 designates the stem of the reversible gage, which is received by and passes through the loops 6 6 of the holder 5. This stem is

formed, with a longitudinal slot 11 there- 50 through, on each side of which slot and on both sides of the stem the latter is transversely corrugated, as shown at 12 12.

13 designates the head of the gage, the said head having slots 14 14 cut in its edges for 55 the reception of the upper edge of the hatchet-blade 2, these two slots being provided so that the gage may be adapted for use with either the right hand or the left hand, as de- 60 sired.

When the gage-stem has been slipped the required distance into the holder according to the desired overlap of the shingles, it is held in this adjusted position by a clamp-block 15 of a width just sufficient to slip be- 65 tween the opposed side walls of the holder 5, the clamp-block being corrugated on its under side to engage with the corrugated portions 12 of the gage-stem and having a central opening for the reception of the threaded 70 shank 16 of a thumb-screw 17, which shank passes through the slot 11 of said gage-stem and engages with the threads of the bore 7 in the bottom wall of the gage-holder 5.

With my device the use of the usual chalk-line or gage-line may be entirely dispensed with and even the projection of the first course of shingles over the eaves may be rendered accurate and even by placing the cutting edge of the hatchet-blade against the 80 cornice or other part of the roof and allowing the shingles to abut against the gage-head 13, and then after this for all the subsequent courses of shingles the hatchet, properly adjusted as described, is used as shown 85 in Figs. 1 and 2, with the gage-head 13 held up against the butts of the shingles in each course and the butts of the shingles in the course above brought down, as shown, against the driving-head or hammer 4 of the hatchet, 90 and, as heretofore referred to, the device can be quickly adjusted for left-handed work by loosening the thumb-screw 17 and withdrawing and reversing the gage-stem 10, and then again adjusting the gage and tightening it to 95 place.

While especially designed for shingling-hatchets, it is obvious that my described ad-

justable gage may be attached to and used with slaters'hammers in substantially the same way.

Having thus described my invention, what I claim as new, and desire to secure by Letters

5 Patent, is—

1. An adjustable gage for shingling-hatchets and like tools, comprising an open - topped gage-holder permanently secured to the handle of said tool, and formed with loops at 10 each end and a tapped bore in its bottom wall; a gage-stem received by and passing through said loops, said stem having a longitudinal slot therethrough, and formed with corrugated surfaces on each side of said slot; a 15 transverse head on one end of said gage-stem; a clamp-block having a central hole therethrough, and corrugations on its under side; and a thumb-screw passing through the hole in the clamp-block and slot in the gage-stem, 20 and engaging with the bore in the gage-holder.
2. The combination with a shingling-hatchet

having a straight-topped blade and a driving-head, an interposed eye or handle-socket, with a handle in said eye or socket, a gage-holder permanently secured to the upper end of said handle, and formed with loops at each end; a reversible and longitudinally-adjustable gage-stem received by and passing through said loop; means for securing said gage-stem in adjusted position, and a transverse gage-head at one 30 end of said gage-stem, said head being formed with slots in the opposed side edges thereof for engagement with the upper edge of the hatchet-blade.

In testimony that I claim the foregoing I 35 have hereunto set my hand, at Milwaukee, in the county of Milwaukee and State of Wisconsin, in the presence of two witnesses.

LESTER STOWELL.
